UNITED STATES PATENT OFFICE.

DE WITT CLINTON PRESCOTT, OF MARINETTE, WISCONSIN.

BAND-SAW MILL.

SPECIFICATION forming part of Letters Patent No. 369,881, dated September 13, 1887.

Application filed February 23, 1887. Serial No. 228,599. (No model.)

To all whom it may concern:

Be it known that I, DE WITT CLINTON PRESCOTT, a citizen of the United States, residing at Marinette, in the county of Marinette and State 5 of Wisconsin, have invented certain new and useful Improvements in Band-Saw Mills, which are fully set forth in the following specification, reference being had to the accompanying drawings, in which—

10 Figure 1 represents a front elevation of the upright portion of a band-saw mill containing my improvements and showing the mounting of the upper band-wheel, said wheel being largely broken away; Fig. 2, a vertical section 15 of the same, taken on the line xx , Fig. 1; Fig. 3, a detail plan section taken on the line yy , Fig. 2; Fig. 4, a similar view taken on the line zz , Fig. 2; Fig. 5, a similar view taken on the line uu , Fig. 2; and Fig. 6, an illustrative elevation showing the relation of a band-saw, its 20 wheels, and the log when the mill is in operation, this last figure not being made, however, on any particular scale.

My invention relates to that class of saw-mills called "band-mills," and may be said to 25 be an improvement upon the mill shown and described in my prior application, Serial No. 207,142, filed July 3, 1886.

The object of the present invention is to provide 30 for adjusting the upper band-wheel and to make the adjusting device exceedingly sensitive, so that the slightest change in strain will effect a movement of the said wheel, thereby taking up even slight slack almost instantly 35 and keeping the saw always under proper strain.

I will proceed to describe one way in which I have carried out my invention in practical form, and will then point out definitely in the 40 claims the special improvements which I believe to be new and wish to protect by Letters Patent.

The mill may be in its main features substantially like that shown in my said prior application, and for this reason I have not shown in the drawings the entire structure, nor shall I attempt to describe it in the present case. At the same time I desire to say that the present improvements are not applicable alone to 45 a mill constructed upon the plan described and shown in the said prior application, but may

be applied to other structures, with, perhaps, such slight modifications as may be necessary to adapt the devices to differences in the main portions of the mill.

55 In the drawings, A represents the base, upon which is mounted a hollow column, B, which constitutes the upright portion of the main frame. This column, as in my former case, consists of two parts—a lower section, b , which is fastened permanently to the base, and is therefore stationary, and an upper section, b' , which is telescoped upon the upper portion of the stationary part b and is movable vertically thereon. In my former structure, referred to above, this upper section has appeared in the form of a closed cap; but in the present instance I leave both ends of this section open, so that ready access may be had to the interior of the upper end of the column. A 60 bracket, a , is secured to the stationary portion of the column and constitutes a hanger for one end of the shaft c of the lower band-wheel, C. The lower portion of the stationary part of the column is enlarged somewhat, 65 at least on one side thereof, and in this portion, near the base, is cut a man-hole, b^2 , as shown in Fig. 2 of the drawings, whereby access may be had to the interior of the column at its base. The upper or movable section of 70 the column is supported by a strong short post, b^3 , which is threaded, and enters a suitably-threaded socket or nut, a' , in the upper portion of the hanger a . The upper end of the post is journaled in a cross-piece or any 75 suitable projection on the lower end of the movable part b' , and may be turned by a hand-lever, b^4 , for the purpose of adjusting the movable section b' , this post operating as a sort of jack-screw for the purpose. It will be noticed 80 that in the drawings this supporting device is located in front of the column. This arrangement is desirable, because the upper band-wheel is also located on the same side of the column, so that here is the greater weight, and 85 the location of the support here will be very nearly at the middle of the entire weight on the section b' , quite sufficiently near for practical purposes. A bracket, D, is attached to the lower end of the movable section b' . This 90 bracket projects outward horizontally a short distance from the column, and is then turned 95

upward at a right angle, being projected up about as high as the upper end of the section to which it is attached. It is hollow and open at each end. At the lower end of the bracket, 5 where it is attached to the section b' , a slot, d , is cut in the latter, and a similar slot, d' , in the stationary section b , thereby providing an opening from the bracket into the column, and at the elbow of the bracket a slot, d^2 , is cut, 10 being arranged about opposite to the opening d in the column. Just outside of the elbow and on each side of the slot d^2 are lugs d^3 .

At the upper end of the movable section b' a sleeve-bracket, E , is attached, being arranged at the back side of the column or opposite to and in line with the vertical portion of the bracket D . At the lower end of this same movable section, and immediately below the sleeve E , are two horizontal lugs, e , attached to the section and about opposite to the horizontal member of the bracket D . A slot, e' , is cut in the section b' between these last-named lugs, and a similar slot, e^2 , in the stationary section b , for the purpose which will 25 be described presently.

The upper band-wheel, F , is secured to a shaft, f , which is mounted in boxes f' . These boxes are in turn mounted upon bearing-blocks G and G' , the former at the front and 30 the latter at the rear of the column. The bearing-blocks are provided with yokes g , within which the journal-boxes are set and secured by pivot-pins g' , which pins are threaded, so as to be adjustable. The front bearing-block terminates below in a stem, g^2 , which is adapted 35 to fit the upper open end of the bracket D and to slide up and down therein. The rear bearing-block terminates in a similar stem, g^3 , which is adapted to fit the sleeve E and move vertically therein.

A lever, H , is pivoted at one end to the lugs d^3 on the bracket D , and extends inward horizontally through this bracket and the walls of the column into the interior of the latter. A 45 similar lever, I , is pivoted at one end to the lugs e on the other side of the column, and is extended inward horizontally through the slots in the column into the interior of the latter. The inner ends of these levers are 50 pivoted to the lower end of a connecting-rod, J , inside of the column, the upper end of which is pivoted to the short arm of a lever, K , which is also pivoted to a lug, k , on the inside of the upper end of the movable section of the column. This lug is arranged on the side of the column next to the band-wheel, and the lever K extends across nearly to the other side of the column.

As shown in the drawings, the lever H is a 60 single bar, while I and K are double, or composed of two bars bolted together. This is a mere detail of construction, however, as a matter of convenience. A supporting post or rod, h , is attached at its upper end to the stem g^2 of the front bearing-block by a screw-thread connection. The lower end of this supporting-

rod rests upon the lever H a short distance in front of its pivot, and in order to make the device sensitive I prefer to construct the lower end of the rod with a knife-edge, h' , so as to 70 make a knife-edge bearing for the support of the front journal of the upper band-wheel. A similar post or rod, i , is attached by a screw-thread connection to the stem g^3 of the rear bearing-block, and at its lower end is connected by a hinge-joint to the lever I a short distance in front of its pivot. For convenience this post may be divided, as shown in Fig. 1 of the drawings, and provided with a nut and ratchet device, L , for the purpose of 80 adjusting the length of the rod, the upper section of which can, of course, be turned, while the lower one cannot. The device, as shown in the drawings, consists of a sleeve-nut, l , threaded right and left at its opposite 85 ends. This nut receives the ends of the respective sections of the post, which are threaded right and left for this purpose. The nut is provided with external teeth around its center, with which an ordinary ratchet-lever, 90 l' , is arranged to engage, thereby providing an ordinary and well-known device for turning the nut. Obviously the turning of the nut in one direction will force the sections of the support apart, while turning in the other 95 will draw them together, by which operation the rear end of the shaft may be adjusted to bring the shaft into a level position. Any other suitable device may be used for this particular nut for this purpose. The post h is also adjusted suitably in a similar way by turning it in its threaded socket; but as it is not positively connected to the lever at its lower end it is not necessary to divide it.

It is obvious that any vibration of the lever 105 K will cause a vibration of the levers H and I , and consequently a simultaneous adjustment of the two bearing-blocks of the upper band-wheel shaft in a vertical direction. The distance from the outer pivots of the levers H and 110 I to the common pivot at their inner ends within the column is practically the same, as is also the distance between each outer pivot and the bearing-point of the respective supporting-posts upon their respective levers; 115 hence the vertical movement of the bearing-blocks and the journals which they support will be practically the same. It will be seen that if the outer or long arm of the lever K be drawn downward the inner or short arm 120 will be raised, thereby pulling upward the inner ends of the levers H and I , which movement will simultaneously raise the bearings of the upper band-wheel shaft, thereby tightening the saw upon the wheels.

In order to effect a constant pull downward upon the lever K , I attach a rod, M , to the long arm of the lever, which rod, for convenience, is extended down within the column nearly to the base of the latter, and at its lower 130 end is adapted to receive weights m , which are introduced through the man-hole in the base

portion of the column, this hole being made mainly for the purpose of placing and removing these weights. This also permits the weight to be readily increased or diminished, as may be desired. Obviously by this arrangement of levers and weights the shaft of the upper band-wheel is held upward constantly, so as to keep the saw taut upon its wheels, and it is evident from the arrangement of the levers that the adjusting device is very sensitive, so that the least little slack in the saw will be taken up and the latter maintained in that taut condition which is necessary for its satisfactory operation.

15 I am aware that the lower band-wheel in mills of this type has been made adjustable automatically for the purpose of taking up slack. There is, however, an objection to this latter mode of adjustment, which will be explained by reference to Fig. 6 of the drawings. In this figure, N represents the lower band-wheel, O the upper wheel, and P the saw, these wheels and the saw running in the direction indicated by arrows. A portion, Q, of the log carriage is also shown with a log, R, thereon and the saw in operation. Guides p p' for the saw are arranged as usual, one above and one below the log. Now the momentum of the wheel produces what is known as "overthrow" 25 of the saw as the latter runs over to the front from the upper wheel. This overthrow produces a slight slack in the saw between the point where it leaves the upper band-wheel and the point where it enters the log—that is, 30 between the points indicated by 1 and 2 in Fig. 6 of the drawings. It is not serious, but sufficient to destroy the proper action of the saw. When the adjustment for taking up slack is made at the lower band-wheel, this 35 overthrow slack must be taken up by pulling the saw back over the upper band-wheel and in opposition to the action of said wheel, for of course it cannot be taken up down through the log while the saw is at work.

40 This action brings an additional strain upon the back portion of the saw and greatly increases the danger of breaking. With the present improvement, whereby the upper band-wheel is made automatically adjustable, 45 it must be obvious that this objection is entirely overcome, for the upward movement of the wheel will take up the overthrow slack immediately and directly. The same remark applies also to the back portion of the saw, 50 for the action is equally direct on that side of the wheel, so that this adjustment of the upper band-wheel takes the slack on both sides directly, thereby preventing extra strain upon the saw, and at the same time keeping the latter perfectly taut while in operation.

55 The proper leveling of the shaft of the upper band-wheel is effected by the adjusting device at the back of the column, whereby the connecting-rod i is made adjustable in length. 60 The alignment of this wheel, to bring it into the same plane with the lower wheel, is effected

by means of the pivot-boxes in which the shaft is journaled. The pivots being threaded, the boxes may be set back and forth in a horizontal direction to perfect the adjustment of the 70 wheel to its proper plane.

I do not wish to be understood as limiting my invention to the precise devices which are herein shown and described. The upper band-wheel shaft may be made automatically adjustable by other devices, and as this is the main characteristic of my invention, I claim it broadly. The special construction and arrangement of the devices which I here employ to secure the adjustment of the said shaft may 75 be varied without materially departing from the improvement as it is here shown embodied. Such modifications may be made without interfering with the invention, and will very likely be required in applying the invention to a 80 band-mill having a supporting-frame different from that herein set forth.

Having thus described my invention, what I claim as new, and desire to secure by Letters Patent, is—

1. In a band-saw mill, the upper band-wheel shaft, in combination with independent vertically-movable bearings, in which the ends of said shaft are separately mounted, and automatic adjusting mechanism applied to each of 95 the bearings of said shaft, substantially as and for the purposes specified.

2. In a band-saw mill, the vertically-adjustable column-section b', in combination with vertically-adjustable bearings for the upper 100 band-wheel shaft mounted on said movable section, and automatic adjusting mechanism applied to said bearings, whereby the upper band-wheel is adjusted, substantially as and for the purposes specified.

3. In a band-saw mill, the horizontal levers H and I, pivoted to the supporting-frame and extending inward toward each other, in combination with the upper band-wheel shaft, 110 vertically-adjustable bearings for said shaft, supports for said bearings sustained at their lower ends by said levers, respectively, and an automatic device applied to the inner ends of said levers and continuously operating to draw them upward, substantially as and for the purposes specified.

4. In a band-saw mill, the horizontal levers H and I, pivoted to the supporting-frame, in combination with the vertically-movable bearings of the upper band-wheel shaft supported 120 by said levers, the lever K, connecting-rod J, and weight m, applied to the lever K, substantially as and for the purposes specified.

5. The upright hollow column, in combination with the horizontal levers on which the 125 bearings of the upper band-wheel shaft are mounted, the lever K, mounted at the upper part and within said column, the rod J, connecting said horizontal levers and the lever K, the weight-rod M, and the weight m, arranged within the column, substantially as and for the purposes specified.

6. The upper band-wheel shaft, in combination with the bearing-blocks G and G', terminating in stems, substantially as specified, the sleeve-supports D and E, adapted to receive the stems of said blocks, the supporting rods *h* and *i*, and the supporting and adjusting levers H and I, substantially as and for the purposes specified.

7. The hollow column B, composed of stationary section *b* and movable section *b'*, provided with vertical registering slots therein, substantially as specified, in combination with the adjusting-levers H and I, pivoted to the movable section *b'* and extending inward through said slots to the interior of the column, the vertically-adjustable bearings of the upper band-wheel shaft, supported by said levers, and a weight applied to the inner ends

of said levers to constantly pull them upward, substantially as and for the purposes specified. 20

8. The supporting and adjusting levers H and I, in combination with the upper band-wheel shaft, the bearing-blocks for said shaft, the front supporting-post, *h*, resting on the lever H with a knife-edge bearing, and the rear supporting-post, *i*, divided as described, and pivoted to the lever I, and a threaded nut applied to the free ends of the sections, whereby they may be moved to and from each other, substantially as and for the purposes 25 specified.

DE WITT CLINTON PRESCOTT.
